C. H. KORS.
NORMALLY CLOSED RECEPTACLE.
APPLICATION FILED JUNE 13, 1917.

1,295,765.

Patented Feb. 25, 1919.

Inventor
C. H. KORS.
By his attorney

Bartlett Moore Jr.

UNITED STATES PATENT OFFICE.

CHARLES H. KORS, OF POUGHKEEPSIE, NEW YORK.

NORMALLY CLOSED RECEPTACLE.

1,295,765.

Specification of Letters Patent. Patented Feb. 25, 1919.

Application filed June 13, 1917. Serial No. 174,429.

To all whom it may concern:

Be it known that I, CHARLES H. KORS, a citizen of the United States, residing at Poughkeepsie, Dutchess county, New York, have invented a certain new and useful Improvement in Normally Closed Receptacles, of which the following is a full, clear, and exact description.

My invention relates to normally closed receptacles and has for its object to provide a new and improved automatically acting closure for such receptacles. It further has for its object to provide a receptacle in which the closing device can be moved laterally so as to permit access to all portions of the receptacle.

It further has for its object to provide means for ventilating such receptacles. It is particularly applicable for use in tobacco factories for containing the filler used in making cigars and the like, but is also useful in other relations.

The following is a description of an embodiment of my invention, reference being had to the accompanying drawings, in which:

Figure 1 shows a front elevation of a receptacle embodying my invention;

Fig. 2 is a side elevation of the same, parts being broken away to show internal features;

Fig. 3 is a section on the line 3—3, Fig. 2;

Fig. 4 is a partial section on the line 4—4, Fig. 1, and

Fig. 5 is a detail.

Referring more particularly to the drawings, 1 is a receptacle in the form of a box having a removable cover 2 for the introduction of material to be contained therein.

40 The front face 3 is cut away at its lower portion so as to leave an opening extending lengthwise of the face and located at the lower portion of the box. Adjacent to the two ends of the opening are two counter-balancing spring rollers 4, 5, each carrying a section 6 of an impervious curtain. The two free ends of the curtain are connected at 7—7 to a frame 8 moving in suitable guide-ways extending across the front of the container, and carrying an extension 9 adjacent to the bottom of the opening, side walls 10 and an abutment 11. 12 is a door hinged at its lower end 13 to the extension 9 and provided with a spring 14, which nor-

55 mally tends to move the upper end of the door upward into engagement with the abut-

ment 11. The said walls 10 extend upwardly from the extension 9 and are adjacent to the sides of the door 12 so that when the door is in the position shown in Fig. 4 60 the receptacle is closed. When it is desired to reach into the receptacle the hand is pressed against the door, which then moves to the position shown in dotted lines in Fig. 4, thus opening the receptacle for the removal of a portion of its contents. When the door 12 is in the position shown in dotted lines in Fig. 4, the hands of the user may rest upon it while manipulating some of the removed contents. When the hands 70 are withdrawn the door automatically rises to closed position. The spring rollers 4 and 5 take up the slack in the curtain sections 6 so that the extension 9, walls 10 and abutment 11 can be moved laterally in either 75 direction, so as to permit easy access to all portions of the receptacle,—the moving portion, on account of counterbalancing and light friction, remaining in any position in which it may be moved.

In order to remove any excess moisture which may be present in the contents of the box, such moisture being apt to accumulate in filler tobacco in hot, damp weather, I provide air inlets 15, closed by a damper 16, 85 and also provide an exhaust port 17 connected to the ordinary suction system 18 commonly employed in cigar factories. This connection is controlled by a cock 19. The exhaust port 17 is preferably in the 90 form of a perforated head. The container is provided with a perforated false bottom 20 located slightly above the exhaust port 17. The suction system causes air to pass in through the openings 15 and through the 95 contents of the box so as to keep up a good circulation and remove any superfluous moisture when conditions require it. Under other conditions, the exhaust port can be cut off by means of the valve 19 and the 100 ports 15 closed by the damper 16, and moistening pads introduced if more moisture is desired. 21 is a removable moistening tray adapted to contain water or moistening pads and carried by a removable wall 105 section 22.

As will be evident to those skilled in the art, my invention permits of various modifications without departing from the spirit thereof or the scope of the appended claims. 110

What I claim is:

1. In a normally closed receptacle, the

combination of a container having an opening in its front face, an extension projecting from adjacent to one edge of said opening, a door hinged at one edge to said extension and extending therefrom in a slanting direction toward the plane of said face, and walls extending from the plane of said extension and adjacent to opposite sides of said door, said door normally tending to move to closed position.

2. In a normally closed receptacle, the combination of a container having an opening in its front face, an extension projecting from adjacent to the lower edge of said opening, a door hinged at one edge to said extension and extending therefrom in an upwardly slanting direction toward the plane of said face, walls rising from the plane of said extension and adjacent to opposite sides of said door, and means for holding said door normally closed.

3. In a normally closed receptacle, the combination of a container having an opening in its front face, an extension project-

ing from adjacent to one edge of said opening, a door hinged at one edge to said extension and extending therefrom in a slanting direction toward the plane of said face, walls rising from the plane of said extension and adjacent to opposite sides of said door, means for holding said door normally closed, and a laterally movable curtain carrying said extension and rising walls.

4. In a normally closed receptacle, the combination of a container having an opening in its front face, an extension projecting from adjacent to one edge of said opening, a door hinged at one edge to said extension and extending therefrom in a slanting direction toward the plane of said face, walls extending from the plane of said extension and adjacent to opposite sides of said door, means for holding said door normally closed, a laterally moving curtain carrying said extension and rising walls, and counter-balancing spring rollers carrying the ends of said curtain.

CHARLES H. KORS.
